(57) **CLAIM**

The ornamental design for a fluid connector, as shown and described.

DESCRIPTION

FIG. 1 is a front right perspective view of a fluid connector showing our new design;

FIG. 2 is a front view of the design shown in FIG. 1;

FIG. 3 is a rear view of the design shown in FIG. 1;

FIG. 4 is a left side view of the design shown in FIG. 1;

FIG. 5 is a right side view of the design shown in FIG. 1;

FIG. 6 is a top view of the design shown in FIG. 1; and,

FIG. 7 is a bottom view of the design shown in FIG. 1.

The dash-dot-dash broken lines in FIGS. 1 and 4-7 illustrate the boundary of the claimed design which forms no part thereof. The broken lines shown in the figures are included for the purpose of illustrating portions of the fluid connector and form no part of the claimed design. The ends of the fluid connector are shown with symbolic break in its length. The appearance of any portion of the article beyond the break forms no part of the claimed design.
